UNITED STATES PATENT OFFICE.

JAMES H. LA PEARL, OF LOS ANGELES, CALIFORNIA.

CHANGEABLE PRISMATIC SIGN.

1,112,921.

Specification of Letters Patent.

Patented Oct. 6, 1914.

Application filed June 1, 1914. Serial No. 842,104.

To all whom it may concern:

Be it known that I, JAMES H. LA PEARL, a citizen of the United States, residing in the city of Los Angeles, county of Los Angeles, and State of California, have invented a new and useful Changeable Prismatic Sign, of which the following is a specification.

My invention relates to the construction of a device which will display in succession a series of signs thereby giving the device many times the capacity of an ordinary sign of the same size.

The device also has power of attracting attention not possessed by a stationary sign, due to the intermittent mechanical movement which is visible from the front of the sign.

The object of the invention is to secure a changeable sign of durable construction having a minimum number of parts and a maximum capacity of display surface. The means by which these results are attained is described herein and is shown in the accompanying drawings, in which:

Figure 1 is a perspective view showing the sign during the interval when it is changing from one display to another, Fig. 2 is an end view of the sign with the outer side casing omitted to illustrate the operating mechanism. Fig. 3 is a fragmental section taken on the dotted line *a—a* in Fig.

1. Fig. 4 shows the same parts after the prism has come to rest and before the leaves are moved into position between the prisms.

Fig. 5 is a perspective view of a prism with two of the leaves attached, showing how it appears when in position to display the sign. Fig. 6 is a perspective view of a

spring locking bar used in the device. Fig. 7 is a similar view of a ratchet arm. Fig. 8 is an elevation of a spring. Figs. 9 and 10 are respectively end and side views of a leaf raising arm and gear. Figs. 11 and 12 are similar views of leaf lowering mechanism.

Throughout the several views like characters indicate like parts.

The sign consists principally of a series of intermittently revolving prisms, leaves for closing the spaces between the prisms and operating mechanism.

In the drawings the prisms are indicated by the numeral 20. In the type of sign illustrated in the drawings, two of these prisms are used. Each prism is provided

with four leaves designated as 21, 22, 23 and 24. The number of sides on the prism is varied according to the number of changes desired, and the number of leaves always equal the number of sides on the prism, one leaf being hinged to each longitudinal edge.

Space must be left between the prisms to permit of their turning. The purpose of the leaves is to close these spaces on the front of the sign. The space between the adjacent faces of any two prisms, when the front faces are in a plane, is made exactly twice the width of a single leaf. Two leaves are therefore necessary to close each space. This is a vital feature of the invention.

By using two leaves to close each space, one of which is raised into place, the other lowered, it is possible to utilize both sides of each leaf for display, in connection with the several prism faces. For any given area of display the number of prisms is therefore less than necessary in signs in which the space between the adjacent prisms is closed by a single leaf, in which case only one side of each leaf can be utilized.

The operating mechanism consists of any suitable motive power indicated as 30. Power is transmitted from this source through a worm 31 to a gear 32 which revolves at a uniform speed. Many well known forms of transmission may be used for the same purpose.

33 is a pin on the gear 32 which once during each revolution strikes and depresses a lever 34. Motion is thence transmitted through the connecting link 35 to a lever 36 which in turn transmits motion through a link 37 to the lever 38, thence through the connecting bar 39 to a ratchet arm 40 and through the reciprocating bar 41 to a second ratchet bar 40 operating the upper prism.

By tracing the direction in which force is transmitted it will be found that the bar 41 moves upward when the lever 34 is depressed and the amount of this upward motion is just enough to move the ratchet arm through an angle of ninety degrees around the shaft 29 as a center. After depressing the lever 34 the pin 33 immediately comes into contact with and depresses the lever 36. The effect of this is to move the bar 41 and connected ratchet arms downward to the position originally occupied by them. The pin 33 is then free to move until it again strikes the lever 34. The effect

sought for and attained in the portion of the operating mechanism above described is to impart to the bar 41 and attached ratchet arms 40, an intermittent up and down motion.

5 The ratchet bars 40 are loosely hung upon the shaft 29. Cross arms 42 are rigidly attached to the shaft 29. These cross arms are preferably flexible and are usually made 10 of spring metal. Each of these arms 42 has a projecting pin 43 adapted to be engaged in an aperture 44 in the ratchet arm 40. The length of the pin 43 is equal to or less than the thickness of the ratchet arm 40. 15 45 is a flat, semicircular spring attached to the wall 27.

27 indicates inside end walls of a box like frame 26 which incloses nearly all of the operating mechanism and this end wall 27 also provides bearings for the shafts 29 supporting the prisms 20.

46 is a spring locking bar also attached to the wall 27.

25 refers to hinges used to fasten the leaves to the prisms. Any form of hinge 25 may be used which will permit the leaf to move through an angle of two hundred and seventy degrees.

The revolving and locking of the prisms 30 is accomplished in the following manner: At the beginning of the upward motion of the ratchet arm, hereinbefore described, the pin 43 on the cross arm 42 is engaged in the aperture 44 and as the ratchet arm is moved upward the cross arm 42 is moved with it. 35 The cross arm is pressed outward from its normal position and held against the ratchet arm by the spring 45 until the end of the upward motion when the cross arm slips 40 over the shoulder in the spring 45 and thus being allowed to resume its normal shape, springs inward disengaging the pin 43 from the ratchet arm 40. In Fig. 8 one cross arm 42 is shown just after it has been pressed 45 outward by the spring and another is shown in its normal position after passing over the shoulder in said spring 45. The prism 20 is attached to and turns with shaft 29 and cross arms 42. The shoulder in the spring 50 presents the cross arm and prism from turning backward while the ratchet arm is moving downward, and the pin 43 on the following cross arm is engaged by the edge of the locking bar 46 which prevents further forward motion of the prism. Immediately before the end of the downward movement of the ratchet arm it enters beneath the curved edge of the locking bar and forces the locking bar outward from the cross arm until 55 the pin 43 is released. The ratchet bar passes over the end of the pin 43 depressing the cross arm and spring 45 until the pin 43 passes under and into the aperture 44 at the end of the downward motion. The edge of 60 65 the ratchet arm is beveled where the pin 43

passes under to prevent the pin from catching on the bar and to gradually depress said pin. In this manner the prisms are intermittently turned a part of a revolution sufficient to present a new face. In the device as shown a quarter of a turn is made each time. With a prism having three sides each upward motion would turn the prism one third of a revolution, with six faces one sixth of a revolution, and so on.

75 The leaves are raised and lowered by means of a rack and pinion device operating simultaneously with the bar 41 and connected with the bar 41 by means of a lever 50.

51 is the rack meshing with the pinions 52 and 53. The pinion 52 is attached to a shaft 54 passing through the wall 27.

55 is a grooved lowering arm on the inner end of the shaft 54. The pinion 53 is similarly mounted on a shaft 56 having on its inner end a raising arm 57.

80 In Fig. 3 the dotted lines show the position of the arms 52 and 53 at the beginning of the upward movement of the bar 41. The solid lines in the same figure show the position when the upward motion is half completed and the solid lines in Fig. 4 show the positions of the same parts at the instant the upward motion is completed. It will thus be seen that during the upward motion of the bar 41 the raising arms are describing a downward semi-circle while the lowering arms are describing a similar upward course.

85 Pins 60 are placed on the ends of the leaves adapted to be engaged by the arms 52 and 53.

90 When prisms are in a position shown in Fig. 4 the pin 60 on the leaf 22 is in the upper end of the groove in the lowering arm 55 which has just completed its upward semicircle to meet this leaf. When the bar 44 starts downward the lowering arm also starts downward and the pin 60 remaining in the groove causes the leaf to follow the arm until it is lowered to a vertical position. The raising arm during this same time is describing a semicircle in an upward direction and, encountering the pin on the leaf 23, raises that leaf to a vertical position. The lower leaf of one prism and the upper leaf of the next prism below entirely closes the space between the prisms and with the exposed sides of the prisms a continuous display surface is thus provided, while the upper leaf of the upper prism and the lower leaf of the lower prism serve to close the spaces between the prisms and the top and bottom of the frame 26.

95 In large signs having long prisms and leaves, it is desirable to have raising and lowering mechanism at each end of each leaf. To accomplish this two sets of racks, pinions, raising and lowering arms are provided and these are caused to operate simul-

- taneously by means of a shaft 70 extending from side to side of the sign, parallel with the shafts 29, and having pinions 71 on the two ends of said shaft 70. On one end a pinion 71 enmeshes the rack 51 as shown and on the opposite end it enmeshes a duplicate rack, not shown, which in turn operates pinions and raising and lowering arms exactly as shown and described above.
- 10 The advertising matter on the faces of the prisms and on the leaves may be painted thereon or printed on paper and then pasted thereon.
- 61 is a stop which prevents the leaf 22 from falling forward after it is raised into place and 62 is a guide attached to the end wall 27 and serves to guide the leaves as they start to the back of the sign.
- Having thus described my invention what 20 I claim as new and desire to secure by Letters Patent is:
1. In a sign, the combination of a series of prisms spaced to permit of simultaneous rotation; leaves hinged to each of the longitudinal edges of each of said prisms; means for partially rotating said prisms at predetermined intervals; means for raising the leaf attached to the upper front edge of each prism, after each partial rotation of said prism, and means for lowering the leaf attached to the bottom front edge of each prism, after each partial revolution thereof.
  2. In a sign, the combination of a series of prisms spaced to permit of simultaneous rotation; leaves, one attached to each longitudinal edge of each prism, the width of each leaf being substantially equal to one half the distance between said prisms when the adjacent faces of the said prisms are parallel; means for partially rotating said prisms at regular intervals; means for raising the leaf attached to the upper front edge of each prism and means for lowering the leaf attached to the lower front edge of each prism until the said leaves are in alinement with the front surfaces of said prisms.
  3. In a sign, the combination of a series of rotatably mounted prisms having parallel longitudinal axes; leaves adapted to close the spaces between said prisms, one hinged to each longitudinal edge of each prism; means for partially rotating said prisms at regular intervals; means for raising the leaf attached to the upper front edge of each prism and means for simultaneously lowering the leaf attached to the lower front edge of each prism after each partial revolution of said prisms, all substantially as described and for the uses and purposes set forth.
  4. In a sign, the combination of a series of rotatably mounted prisms having parallel longitudinal axes; leaves attached to the longitudinal edges of said prisms, adapted to close the spaces between the front surfaces of said prisms, prism rotating mechanism
- consisting of power mechanism adapted to transmit reciprocal motion to ratchet bars; ratchet bars adapted to engage and move in succession cross arms attached to said prisms; means for releasing said cross arms from said ratchet bar at the end of each forward motion of the ratchet bar; means for raising the leaves attached to the top front edges of said prisms and means for lowering the leaves attached to the lower front edges of said prisms, after each partial rotation of said prisms.
5. In a sign, the combination of a series of rotatably mounted prisms having parallel longitudinal axes; leaves attached to the longitudinal edges of said prisms; prism rotating mechanism consisting of a ratchet bar adapted to engage successively the cross arms attached to each of said prisms; cross arms attached to each prism, one arm for each face to be exposed, a reciprocating bar connecting the said ratchet bars, driving mechanism adapted to intermittently move said connecting bar and attached ratchet bars, and means for releasing the cross arms from said ratchet bars at the end of the forward movement of said connecting bar; means for locking said prisms after each partial rotation; means for moving the leaves into alinement with the faces of the prisms thus closing the spaces between the said prisms.
6. In a sign, the combination of a series of rotatably mounted prisms having parallel longitudinal axes; leaves hinged to the longitudinal edges of each prism; means for partially rotating said prisms at intervals; a rack operatively connected with the prism rotating mechanism; pinions, two for each of said prisms, enmeshing said rack; shafts to which said pinions are attached, said shafts being opposite and in alinement with the front top and bottom edges of each prism; raising arms attached to the said shafts opposite the top edges of said prisms, each of said arms being adapted to raise a leaf attached to said top edge of the adjacent prism; grooved lowering arms attached to the pinion shafts opposite the lower front edges of each of said prisms, adapted to lower the leaves attached at the lower front edges of said prisms, thus closing the spaces between said prisms.
7. In a sign, the combination of a series of rotatably mounted prisms having parallel longitudinal axes; leaves attached to the longitudinal edges of said prisms; prism rotating mechanism consisting of cross arms attached to said prisms, ratchet bars adapted to engage said cross arms, a bar connecting said ratchet bars, driving mechanism adapted to intermittently move said connecting bars and means for releasing said cross arms from said ratchet bars at the end of each forward motion of said connecting bar;

means for locking the prisms after each partial rotation; and leaf lowering and raising mechanism consisting of a rack operatively connected with said connecting bar, pinions engaged by said rack, shafts carrying said

lower front edges of said prisms and raising arms attached to the said shafts opposite the top front edges of said prisms.
